ROCKER ARM

John F. Cailloux and Philip M. Rea,
Oklahoma City, Okla.

Application March 4, 1937, Serial No. 128,952

11 Claims. (Cl. 74—559)

The invention relates to rocker arms used as means for actuating a valve rod from a reciprocating piston rod.

The present design is primarily intended for use in connection with oil well slush pumps of a type consisting of a power piston and chamber and, spaced therefrom and in alinement therewith, a pump piston and chamber, the two pistons being connected by a piston rod, and the power chamber being equipped with a control valve for regulating flow of a power fluid to and from the chamber. The rocker arm together with a crank act as a driving connection from the piston rod to a valve rod which is usually mounted for reciprocation upon an axis parallel with that of the piston rod.

The prime object of the invention is the provision of a connecting structure between the two rods which will be sufficiently flexible to eliminate tendency to bind and at the same time will positively drive the valve rod in an opposite direction and in proper timed relation with the motion of the piston rod.

Other objects of the invention are: the provision of a mechanical structure of the class described which absorbs practically all of the shock occasioned by reversing direction of movement of the two rods, thus obtaining a smooth operation devoid of jar and clatter; which permits a free rotation of the two pistons, thus avoiding to a great extent the scoring of the chamber walls and wear upon the pistons; which may be readily disassembled for replacement of worn parts; which lends itself easily to adaption upon many standard makes of slush pumps now in general use; which is sturdy and durable; and, which is efficient in accomplishing all of the purposes for which its use is intended.

In the drawings:

Figure 1 is a side elevational view of a pump unit with the preferred embodiment of the rocker arm thereon;

Figure 2 is a perspective view of the device with portions of its connecting members being removed;

Figure 3 is a perspective view of the annular bearing housing;

Figure 4 is a fragmentary sectional view taken substantially in a plane indicated by the lines 4—4 of Figure 2;

Figure 5 is a fragmentary detail of a portion of one of the yoke legs;

Figure 6 is a partial longitudinal sectional view taken in a plane indicated by the line 6—6 of Figure 2; and,

Figure 7 is a longitudinal sectional view taken in a plane indicated by the line 7—7 of Figure 2.

Like characters of reference designate like parts in all of the figures.

Referring now more particularly to Figure 1 of the drawings, the reference numeral 1 indicates as a whole the power end or unit of a pumping organization, the pumping end or unit of which is indicated by the reference numeral 2. The two units 1 and 2 are usual, and each comprises a piston chamber and a piston therein, the two chambers being in axial alinement and the two pistons being connected by a piston rod 3. The power unit 1 is, as usual, equipped with a power fluid control valve, not shown, adapted to be operated by the reciprocation of a valve rod 4. The units 1 and 2 are held in their alined and spaced positions by a brace or bridge 5 which is integral with and supports an upstanding bracket 6 journalling a rockshaft 7. The hidden end of the rock-shaft is keyed to a perpendicularly extending crank-arm, not shown, and the free end of the crank-arm is pivotally connected to the free end of the valve rod 4. Consequently, rocking motion of the rock-shaft 7 causes reciprocation of the valve rod 4 in an obvious manner.

The structure described in the above paragraph is usual in the art.

The device of the present invention is best shown as a whole in Figure 2 of the drawings, and consists substantially of a piston rod coupling structure A, a female telescoping arm element B, and a male telescoping arm element C thereabove.

The element C consists substantially of a bifurcated head having parallel upstanding walls 10 and 11 connected at their lower portions by an integral floor 12 the upper surface of which is preferably arcuate. Integral with and depending from the floor 12 is a tubular plunger 13 having a plurality of lateral perforations 14, the office of which will be more fully described hereinbelow. The floor 12 is perforated as indicated at 15 to form a continuation of the bore in the plunger 13.

Depending from the nether surface of the floor 12 and surrounding the plunger 13 in spaced relation to the exterior surface thereof is a guard sleeve 16. The office of the sleeve 16 will be more fully described hereinbelow.

The head is provided with fluid inlet bores 17 which communicate from the exterior of the sides 10 and 11 to the bore of the plunger 13.

Pivots mounted between the walls 10 and 11

of the head upon a pivot pin or bolt 18, is a block 19 which is bored to receive the shaft 7 to which it is keyed.

The piston rod coupling structure A consists substantially of an all-thread nipple 20 having an exterior annular shoulder 21 against which is seated an annular shock absorbing ring 22 of a suitable resilient material. A heavy sleeve 23 surrounds the exterior surface of the nipple 20 and the nipple is permitted free rotation therein. A second and similar shock absorbing ring 22 is seated against the end of the sleeve 23, and it will be noted that portions 24 of the sleeve surround and confine the rings 22. Intermediate its ends the sleeve 23 is equipped with two oppositely disposed perpendicularly outstanding trunnions 25 having their ends exteriorly threaded.

It is common practice in the art to construct the piston rod 3 in two sections, the adjacent ends of the sections being threaded to receive a coupling. In the present instance the two piston rod sections are threadedly engaged within the nipple 20 instead of within a usual coupling. A lock-nut 26 is provided around the piston rod to lock the rod and the nipple 20 against independent rotation, while a jam-nut 27 acts in a similar manner at the other end of the nipple. However, the jam-nut 27 has the additional function of compressing a follower 28 against the ring 22 for anchoring the two rings 22 and the sleeve 23 against longitudinal movement with relation to the nipple 20. The follower 28 has an inwardly projecting flange 29 which is impinged between the jam-nut 27 and the end of the nipple 20 to prevent over compression of the two rings 22. It may be seen that the shock of any force exerted upon the sleeve 23 in a direction longitudinal thereof must be borne by the two rings 22. It will also be noted that while the sleeve 23 is positively held against longitudinal movement with relation to the nipple 20, and consequently with relation to the piston rod 3, the nipple is at all times free to rotate within the sleeve.

The arm element B consists substantially of a tubular shell 30 open at both ends. The shell is equipped with a closed bottomed removable liner 31 held in place within the shell by a pin 32. The liner 31 is of a diameter sufficient to make a comparatively loose working fit about the plunger 13 which it receives, and the exterior diameter of the shell 30 is sufficiently small to barely pass within the sleeve 16 of the arm element C.

The lower end of the shell 30 is bifurcated to form a yoke 33 consisting of two oppositely disposed legs 34 identical in form and having a sufficient spread to envelope the sleeve 23 transversely. The free or lower ends of the legs 34 are each in turn bifurcated to form tines 35, and between the tines on each leg is a bore 36 (Figure 4) adapted to receive a bearing housing ring 37. Usual roller bearings 38 are confined within the ring 37 upon an annular race 39 which closely fits around the trunnion 25.

As a means for holding the ring 37 against rotation within the bore 36, the exterior surface of the ring is provided with a cavity or perforation 40 adapted to seat a lock-ball 41. The comparative size of the cavity 40 and the lock ball 41 are illustrated in dotted lines in Figure 3. A superficial bore or groove 42 (Figure 5) is machined into one of the tines 35 to permit passage of the ball as the bearing is pressed into operative position around the trunnion. A suitable lubricating connection (Figure 4) is provided for the injection of a lubricant to the bearing mem-

bers. A washer 43 and castellated nut 44 act to hold the bearing in place and also to hold the yoke in place upon each trunnion. A clamping bolt 45 extending through the tines 35 acts to draw them into firm engagement with the bearing ring 37.

In operation, it will be understood that the distance between the axis of the piston rod 3, represented by a line 51 (Figure 6) and the axis of rotation of the rock-shaft 1, represented by a line 50 (Figure 6), is at all times constant. The device in its operation must move through positions represented by lines 52, which causes a longitudinal slippage between the plunger 13 and the shell 30. A liquid, for instance oil, is introduced into the bore of the plunger through one of the passages 17, and during operation the liquid has a dampening effect sufficient to give a stabilized pressure within the male and female arm elements. The transverse bores 14 in the plunger together with the loose working fit between the plunger and the liner 31 permits flow of the liquid from the interior of the plunger to the interior of the shell. The opening 15 in the floor 12 of the head precludes the occurrence of a liquid lock between the shell and the plunger. The sleeve 16 acts as a protecting agent to prevent the entrance of foreign substances into the chamber complementally formed by the plunger and the shell.

It has been found in operation that there is usually some little end play in the rock-shaft 1, particularly when a battery of two complete pumping units are connected by two rocker arms to a single rock-shaft. This is the reason for pivotally mounting the block 19 in the head of the element C. The permitted pivotal movement of the block 19 upon the bolt 18 is illustrated in Figure 7 by lines 53.

We claim:

1. The combination with a piston rod, and with a rocker arm for transferring motion from the rod to another mechanical element, said rocker arm consisting of two slidably connected members, of connecting means between the free end of one of the members and the rod whereby the rod is permitted rotation yet is held against longitudinal movement with relation to the arm, and means for rockably connecting the free end of the other member to said mechanical element.

2. Organization as described in claim 1, in which the rocker arm includes two telescoping elements.

3. Organization as described in claim 1, in which the rocker arm includes two telescoping elements complementally forming a chamber for retaining a fluid, and a fluid in the chamber for dampening relative movement of the members.

4. The combination with a piston rod, and with a rocker arm for transferring motion from the rod to another mechanical element, said rocker arm consisting of two telescoping members, of a connecting means between the free end of one of the members and the rod whereby the rod is permitted rotation yet is held against longitudinal movement with relation to the arm, and means for rockably connecting the free end of the other member to said mechanical element.

5. A rocker arm for transmitting motion from a piston rod to another mechanical element, said arm including: two telescoping members one member rockably connected to the rod, and the other having operative connection with the mechanical element, said members complementally

forming a chamber for retaining a dampening fluid.

5 6. A rocker arm for transmitting motion from a piston rod to another mechanical element, said arm including: two telescoping members one member rockably connected to the rod, and the other having operative connection with the mechanical element, said members complementally forming a chamber for retaining a dampening fluid, and a fluid in the chamber for dampening 10 relative movement of the members.

10 7. The combination with a piston rod, and with a rocker arm for transferring motion from the rod to another mechanical element, of connecting 15 means between the arm and the rod whereby the rod is permitted rotation yet is held against longitudinal movement with relation to the arm, and shock absorbing means carried by the connecting means for dampening the shock of any force delivered in a direction longitudinal of the 20 rod.

20 8. The combination with a piston rod, and with a rocker arm for transferring motion from the rod to another mechanical element, of a unitary connecting means between the arm and the rod and separable from both, and a shock absorbing means carried by the connecting means for dampening the shock of any force delivered 25 in a direction longitudinal of the rod.

25 30 9. The combination with a piston rod, of a rocker arm for transmitting motion from the rod

to another mechanical element, said arm including two telescoping members complementally forming a chamber for retaining a dampening fluid, connecting means between the arm and one of the members, and a shock absorbing means for dampening shock between the member and the rod of any force delivered in a direction longitudinal of the rod. 5

10 10. The combination with a piston rod, of a rocker arm for transmitting motion from the rod 10 to another mechanical element, said arm including two telescoping members complementally forming a chamber for retaining a dampening fluid, and a fluid in the chamber for dampening relative movement of the members. 15

15 11. The combination with a piston rod formed by two axially aligned elements with their adjacent ends adapted to be connected together for simultaneous movement, and with a rocker arm adapted to be connected to the two elements 20 for transferring motion from the elements to a mechanical arrangement, of a unitary means for connecting the adjacent ends of said elements together and for removably attaching them to the rocker arm, and a shock absorbing means carried by the connecting means for dampening the shock of any force exerted in a direction 25 longitudinal of the rod. 30
